UNITED STATES PATENT OFFICE.

LEOPOLD F. BURGER, OF RIVERSIDE, ILLINOIS, ASSIGNOR, BY MESNE ASSIGNMENTS,
TO INTERNATIONAL HARVESTER COMPANY, A CORPORATION OF NEW JERSEY.

CARBURETOR.

Original application filed April 22, 1918, Serial No. 230,036. Divided and this application filed May 6, 1921. Serial No. 467,383.

This invention relates to carburetors for internal combustion engines and is a division of my application for Letters Patent, Serial Number 230,036, filed April 22, 1918.

More specifically, this invention relates to a carburetor for the heavier fuels such as kerosene, and to a means for supplying moisture to the mixture before it enters the engine cylinders to thereby effect more efficient utilization of the fuel. I have illustrated one embodiment of my invention in the accompanying drawings, in which—

Figure 1 is a horizontal section of my carburetor taken on the broken line 1—1 of Figure 2;

Figure 2 is a front elevation of the same partly in section on the broken line 2—2 of Figure 1;

Figure 3 is a plan view of the carburetor; Figure 4 is a vertical section through the auxiliary air valve on the line 4—4 of Figure 3;

Figure 5 is a vertical section through the water valve on the line 5—5 of Figure 3; and

Figure 6 is a vertical section through the fuel valve on the line 6—6 of Figure 3.

This carburetor comprises a body 11 containing the fuel reservoir 12, the supply chamber 13, and the overflow chamber 14.

The upper part of the body is surmounted by a hooded portion 15 having the air passage 16 partially closed by the auxiliary valve 17, which is pressed by the spring 18, said valve having openings 19 which are always open for the free passage of air. This air passage leads to the downwardly disposed Venturi tube 20, which in turn leads to the inlet valve of the internal combustion engine. Between the supply chamber 13 and reservoir 12 is placed the weir or dam 21, and between the fuel reservoir and the overflow chamber 14 is placed another and lower weir 22. Between the supply chamber 13 and overflow chamber 14 is placed a three-way valve 23, having a longitudinal cavity 25 and a port 24 communicating therewith through the side. Drain passages 28, 29 and 30 lead respectively from the supply chamber, fuel reservoir, and overflow chamber. These passages are all arranged in the same plane with each other and with the port 24 of the rotatable valve 23 so that as the valve is turned it may be brought into registration with any one of

these passages. The longitudinal cavity 25 in the valve 23 opens into a passage 26 into which is tapped the overflow pipe 27, which communicates with the main fuel tank of the engine. A fuel supply pipe 31 is likewise tapped into the supply chamber 13, and this pipe communicates with the fuel pump or other source of fuel supply.

At the throat or narrowest portion of the Venturi tube 20 I have placed an opening 32, which may be regulated by means of the needle valve 33. This needle valve is supplied by means of a tube 34 which reaches down into the fuel reservoir 12, the height of fuel in the reservoir being maintained by the weir 22. A water supply opening 35 is placed in the Venturi tube at the same height as the fuel valve, which is likewise regulated by a needle valve 36. This valve is supplied with water through the chamber 37, in which is placed a check valve 38 which normally closes an opening 39 in the threaded plug 40. This opening is placed directly over a passage leading to the water jacket 41' in the head 41 of the engine cylinder. This valve is so devised that it will overcome water pressure from the water jacket, and prevent water from flowing into the Venturi tube 20 when the engine is not in operation, but will permit it when the engine is running, due to the vacuum produced in the Venturi tube.

The carburetor is preferably mounted upon the cylinder head, and fastened by means of cap screws 42, one of which carries a spring 43 which holds the valve 23 on its seat. The valve has a handle 23^a, with a projection 23^b, which is adapted to strike stops 11^a in the carburetor body 11, which are so placed as to indicate the two working positions of the valve. The top of the carburetor body also contains two openings 11^b and 11^c, which permit the condition of flow of the fuel to be readily observed, and which also supply a ready means for introducing fuel into the fuel reservoir.

The manipulation of the carburetor, when starting with a cold engine, is as follows: The water supply valve 36 is first closed, the three-way valve 23 is then turned to the middle position so as to bring the opening 24 in registration with the drain 29 to the fuel reservoir. Any fuel then in the reservoir is drained through the passage 26 and

the overflow pipe 27 to the main fuel tank. When the fuel reservoir is thoroughly drained the valve 23 is turned so as to bring the port 24 in registration with the opening 28 so as to drain the supply chamber 13, and at the same time to close the fuel reservoir opening into the drain. This is done because I prefer to supply fuel to the supply chamber 13 continuously during the operation of the engine, and it is necessary to turn this valve so as to allow this supply of fuel to pass immediately back to the fuel tank, and not allow it to back up and overflow the weir 21 into the fuel reservoir 12. With the valve in this position gasoline is introduced through the opening 11^b into the fuel reservoir 12, and the engine started.

Enough gasoline is introduced to allow the engine to run until it is thoroughly heated. As soon as that is done, and the supply of gasoline in the fuel reservoir is nearly exhausted, the valve 23 is turned as far in the opposite direction as it will go, or, in other words, until the opening 28 is closed, and the opening 30 from the overflow chamber is brought into registration with the port 24 of the three-way valve.

It will be understood that in the meantime kerosene or other fuel has been continuously supplied to the supply chamber 13, and, as before stated, is allowed to return to the main fuel tank through the overflow pipe 27. The opening 28 now being closed, this fuel will immediately overflow the weir 21 into the fuel reservoir 12, and as soon as this is filled to the height of the weir 22, this heavier fuel will then overflow over the top of this weir in the overflow chamber 14, and thence back through the pipe 27 to the main fuel tank. As soon as the engine has become sufficiently heated to permit, the water valve 36 may be opened, and moisture supplied to the charge received by the cylinder.

What I claim as new is:

1. In a carburetor for an engine having a water jacket, a vertical Venturi tube extending through the body of the carburetor and adapted to have air discharged downwardly therethrough, a fuel reservoir surrounding the Venturi tube, a fuel valve connected to the reservoir and discharging into the constricted portion of the Venturi tube, and a water valve projecting through the fuel reservoir and connected to the water jacket to receive water therefrom, said water valve also discharging into the constricted portion of the Venturi tube at a point adjacent the fuel valve.

2. In a carburetor for an engine having a water jacket, a Venturi tube integral with and extending through the body of the carburetor and adapted to have air discharged therethrough, a fuel reservoir adjacent the Venturi tube, a fuel valve connected to the reservoir and discharging into the con-

stricted portion of the Venturi tube, and a water valve projecting through the fuel reservoir and receiving water through a passage directly connected to the water jacket to receive water therefrom, said water valve also discharging into the constricted portion of the Venturi tube at a point adjacent the fuel valve.

3. In combination with a cylinder having a water jacket, a constant level fuel reservoir, a Venturi tube adjacent thereto, fuel and water valves opening into the Venturi tube at its narrowest portion, a water passage for the water supply leading through the fuel reservoir and directly connected to the water jacket, and a pressure controlled valve in said connection.

4. In combination with an engine cylinder having a water jacket, a carburetor body formed from a single casting and having an integral central vertical Venturi tube formed therein, a fuel reservoir surrounding the tube and having a discharge tube opening into the constricted portion of the Venturi tube, a hooded air intake communicating with the Venturi tube at its upper end, and a water passage formed in the casting and communicating at its opposite ends with the water jacket and with the Venturi tube at its constricted portion respectively.

5. In combination with an engine cylinder having a water jacket, a carburetor, a single piece casting having a vertically disposed Venturi tube formed therein, said Venturi tube adapted to have air discharged downwardly therethrough, a chamber surrounding the tube and forming a constant level fuel reservoir, a fuel intake passage in the casting, a fuel nozzle leading from the reservoir to the throat of the Venturi tube, and a water passage having one end opening through a wall of the casting so as to have direct communication with the water jacket of the engine and the other end discharging into the throat of the Venturi tube.

6. In a carburetor, a single piece casting having a Venturi tube formed therein, said Venturi tube adapted to have air discharged therethrough, a chamber surrounding the tube and forming a constant level fuel reservoir, a fuel intake passage in the casting, a fuel nozzle leading from the reservoir to the throat of the Venturi tube, and a water passage having one end opening through a wall of the casting and the other end discharging into the throat of the Venturi tube, in combination with a valve controlling the passage of air through the Venturi tube, and a pressure actuated valve controlling the water passage.

In testimony whereof I affix my signature,

LEOPOLD F. BURGER,
